CURB FEELER

David Frees, Encino, and Edwin L. Schwartz, Los Angeles, Calif., assignors to Sutone Corporation, Los Angeles, Calif.

Application January 12, 1959, Serial No. 54,145

Term of patent 14 years

(Cl. D14—6)

We claim:

The ornamental design for a curb feeler, substantially as shown.
